Fig. 4

Des. 176,482

PAGE 3

Fig. 5

Fig. 6

Figure 1 is a plan view of a mounting for guillotine gauge, showing my new design;

Figure 2 is a side elevational view;

Figure 3 is an end view looking in the direction of the arrows 3—3 of Figure 1;

Figure 4 is an end view looking in the direction of the arrows 4—4 of Figure 1;

Figure 5 is a perspective view taken from one end of the mounting; and

Figure 6 is a perspective view taken from the other end of the mounting in an upside-down position.

I claim:

The ornamental design for a mounting for guillotine gauge, substantially as shown.
